PHONOGRAPH CABINET

Filed July 22, 1922

Inventor
JOHN PETERSON

By *Paul Paul*
ATTORNEYS

UNITED STATES PATENT OFFICE.

JOHN PETERSON, OF FARIBAULT, MINNESOTA.

PHONOGRAPH CABINET.

Application filed July 22, 1922. Serial No. 576,746.

To all whom it may concern:

Be it known that I, JOHN PETERSON, a citizen of the United States, resident of Faribault, county of Rice, State of Minnesota, have invented certain new and useful Improvements in Phonograph Cabinets, of which the following is a specification.

The object of my invention is to provide a cabinet of such construction that the sound waves will be magnified or intensified to such a degree that spoken words and musical notes will be clear and well defined instead of being mixed and confused, as often is the case with instruments of this kind as ordinarily constructed.

A further and particular object is to provide a phonograph cabinet of a portable type in which the operating mechanism is compactly arranged and provision is made for augmenting or magnifying the sound waves discharged from the cabinet to the end that a comparatively large volume of sound can be obtained by the use of a comparatively small instrument.

Other objects of the invention will appear from the following detailed description.

In the accompanying drawings forming part of this specification,

Figure 1 is a vertical sectional view through a cabinet embodying my invention,

Figure 2 is a plan view with the cover removed,

Figure 3 is a transverse sectional view,

Figure 4 is a longitudinal sectional view showing a slightly modified construction,

In the drawing, 2 represents the side walls of the cabinet, having a suitable cover 3 and a top 4 on which the turntable 5 is arranged, driven by the motor 6 in a chamber 7. The tone arm 8 is mounted in the top 4 and has the usual sound box 9 in which the needle is mounted. From the illustration of my device shown in Figs. 1 or 4 it is apparent that the cover 3 may be closed while the

phonograph is being operated and of course such closure would materially dampen or shut off the sounds emitted from the phonograph. By raising the cover 3 and opening the cabinet the sounds emitted from the phonograph could be correspondingly increased. The device may be used in connection with a radio receiver, and in that case, the radio sound box will be placed on the tone arm, in place of the phonograph sound box, and the radio waves intensified by the action of the vibrating diaphragm or plate

beneath; thus I am able to adapt the device for both phonograph and radio receiver use. Beneath the tone arm is a shallow resonance chamber 10 separated by a partition 11 from the chamber 7 and with this chamber 10 the tone arm communicates.

The top 4 has an opening 12 therein communicating with the chamber 10 and an extension 13 of the tone arm flared at one end fits the underside of said opening concentric with the base of the tone arm. This extension depends to a point preferably about midway of the chamber 10, is spaced from the side walls thereof. Upon each side of the sleeve I prefer to provide openings 14 in the top 4 for the passage of the sound waves. In the bottom of the cabinet I provide a thin floor plate 15, preferably of wood and sufficiently thin to be vibrated by the sound waves when the instrument is in use, the effect of the vibration of this plate being to magnify or increase the volume of sound and at the same time separate the notes and prevent them from running together or becoming confused, which often occurs when notes of a high pitch are played or sung. This plate may be of any suitable thickness that will insure the proper degree of vibration and as shown in Figure 1, it is preferably located in the bottom of the cabinet near the lower end of the extension 13 and fitted into a recess 16 in the lower side walls so that its vibration will not be affected, or interfered with by contact with the table or other support on which the cabinet may be placed.

In Figure 4, I have shown a modification which consists in providing a plate 17 of ordinary thickness for the bottom of the cabinet and in the chamber 10 arranging a thin plate 18 which will vibrate through the action of the sound waves and have substantially the same effect as the plate 15 shown in the other figures.

It will be noted from an examination of the drawings that the resonance chamber below the tone arm is closed at the bottom and sides and that the flaring lower end of the depending extension of the tone arm is near the surface of the diaphragm or floor of the chamber; said diaphragm being parallel substantially with the top wall of the chamber and the sound waves discharged downwardly through the extension of the tone arm striking it undiminished substantially in volume and setting the diaphragm or

floor of the chamber in vibration and directing such waves increased in volume backwardly on a line parallel substantially with the axis of the tone arm toward and through the discharge openings in the top of the chamber. This manner of handling the sound waves I have found by actual test results in augmenting or magnifying the waves to such an extent that the volume thrown out through the discharge openings in the top of the chamber is very materially increased, and I am able to obtain the desired volume of sound in a cabinet that is small and compact and provided with a comparatively shallow resonance chamber. I have found that by locating the discharge openings of the sound box or chamber directly opposite the diaphragm that the waves are not interrupted and the sound is not deadened or muffled as it would be where the discharge opening is in the side wall of the box or cabinet in a plane in angular relation to the vibrating diaphragm or floor instead of parallel therewith.

26 I claim as my invention:

1. An apparatus of the class described comprising a casing having a compartment therein provided with a comparatively thin flat floor plate supported only at its edges and side walls forming a resonance chamber, a top for said chamber having an opening therein and a tone arm fitting over said opening, an extension of said tone arm depending below said top and opening to a point near said plate, said top also having a sound wave discharge opening, the sound waves from said tone arm being directed downwardly by said extension and striking said plate undiminished substantially in volume and at right angles to said plate to cause it to vibrate and increase the volume of such waves and direct them backwardly through said wave discharge opening.
2. An apparatus of the class described comprising a casing having a compartment therein provided with a comparatively thin flat vibratable floor plate and closed side walls at right angles substantially to said floor plate and forming therewith a resonance chamber, a top for said chamber parallel substantially with said floor plate and

having an opening therein and a tone arm fitting over said opening, an extension of said tone arm registering with said opening and depending from said top to a point near said floor plate, said top also having wave discharge openings upon opposite sides of said extension, the sound waves from said tone arm being directed downwardly by said extension against said plate undiminished substantially in volume and causing it to vibrate and increase the volume of such waves and project them backwardly through the openings in said top.

3. A talking machine comprising a cabinet having a compartment therein, sufficiently enclosed to form a vibrating body of air when the machine is operated, said compartment being provided with a comparatively thin plate forming a sounding board, and walls forming a resonance chamber, a wall of said chamber having an opening therein and a tone arm fitting said opening, an extension of said tone arm depending beyond said opening to a point near said thin plate, a wall of the chamber also having a sound wave emitting opening, the sound waves from said tone arm being directed by said extension toward and against said thin plate, causing said thin plate to vibrate and direct them backwardly through said wave discharge opening.

4. An apparatus of the class described comprising a cabinet having a compartment therein provided with a comparatively thin plate, a top plate extending over said compartment and sides forming a resonance chamber, the top plate of said chamber having an opening therein, and a tone arm ending in said opening, an extension of said tone arm extending beyond said opening to a point near said thin plate, said top plate also having a sound wave discharge opening, the sound waves from said tone arm being directed by said extension toward and against said thin plate causing it to vibrate and increase the volume of such waves and direct them backwardly through said wave discharge opening.

In witness whereof, I have hereunto set my hand this 13th day of July, 1922.

JOHN PETERSON.
